UNITED STATES PATENT OFFICE.

HERBERT M. WETHERINGTON, OF VANCEBORO, NORTH CAROLINA.

GATE.

1,252,754.

Specification of Letters Patent.

Patented Jan. 8, 1918.

Application filed July 10, 1917. Serial No. 179,710.

To all whom it may concern:

Be it known that I, HERBERT M. WETHERINGTON, a citizen of the United States, residing at Vanceboro, in the county of Craven 5 and State of North Carolina, have invented certain new and useful Improvements in Gates, of which the following is a specification.

This invention relates to gates, and more 10 particularly to a lockable gate, adapted to be raised and lowered by mechanism automatically operating to maintain the gate in operative position.

One of the principal objects of the invention 15 is to provide a vertically swinging gate adapted to be collapsed, whereby a person may simply press his foot on the gate to bring it to open position; and which will automatically swing to closed position, when 20 the foot pressure is removed.

A further object of the invention is the provision of a gate of this character having means, whereby the gate will be prevented from opening by the wind, and will be maintained in substantially rigid position and 25 free from the ordinary vibration.

A further object of this invention is the provision of a gate which consists of comparatively few parts and is simple in construction, but durable and well adapted to 30 withstand the rough usage to which devices of this character are ordinarily subjected.

For a full description of the invention and the advantages and merits thereof, reference 35 is to be had to the following description and the accompanying drawings, wherein is illustrated the preferred form of my invention, in which:

Figure 1 is a side elevation of the gate, 40 constructed in accordance with my invention.

Fig. 2 is a section on the line 2--2 of Fig. 1.

Fig. 3 is a section on the line 3--3 of 45 Fig. 1.

Referring to the drawing, wherein is illustrated the preferred form of my invention, and in which like numerals of reference indicate corresponding parts throughout 50 the several views, the base 1 may be sunk in the ground at the point at which the gate is to be mounted and is provided at each end with supports 2 having the platform 3 resting thereon. This platform is preferably 55 disposed at the ground level whereby the

platform will provide no obstruction to a person or vehicle using the gate.

Mounted intermediate the ends of the platform is the gate 4 which consists of a plurality of pickets or palings 5, fixed to complementary plates 6. These plates form a clamp member which is pivotally mounted on the platform through the medium of the loops 7 which consist of substantially U-shaped bolts extending through the clamp, 65 and through the platform, and fixed to the bottom thereof.

A rod or shaft 8 is carried by this clamp, and the shaft is embraced by the said loops 7. This shaft 8 is bent at right angles at 70 one end and hangs over the edge of the platform 3, and carries a weight 9, at its end. This weight normally tends to hold the gate in raised position, but it will be obvious that a strong wind might swing the gate and to 75 obviate this, I have provided a lever 10, pivotally mounted on the base 1. This lever has one arm curved to provide a depression for receiving the weight 9, while the opposite end of the lever is weighted so that the 80 curved end will press slightly upon the weight to prevent movement of the gate by the wind.

The connecting arms 11 are fastened to the gate at opposite sides thereof, and each 85 connecting arm projects toward one end of the platform 3 and is joined to a pivoted link 12, clearly shown in detail in Fig. 3 of the drawing. This link consists of a suitable bent rod or the like, pivotally connected 90 to a connecting arm 11, and the platform 3, and having a projected portion 13 carrying a weight 14. It will be obvious that when the gate is pressed downwardly to open position, these weights will swing upwardly 95 and operate to urge the gate back to closed position, after the person or vehicle has passed through.

When a vehicle is to pass through the gate it is simply necessary to drive the vehicle 100 over the platform 3 from either end thereof and press against the gate until the latter swings downwardly for permitting the vehicle to pass over the gate. As the gate swings on its pivot, the weight 9 will be 105 raised and the weights 14 will also be swung to raised position by virtue of the connection established between the links 12 and the connecting arms 11. As soon as the vehicle has passed over the gate, the weights 9 and 110

14 will move back to normal position and thereby raise the gate to its normal vertical position.

From the foregoing it will be observed that a very simple and durable gate has been provided, the details of which embody the preferred form. I desire it to be understood, however, that slight changes in the minor details of construction may be made 10 without departing from the spirit of the invention or the scope of the claims hereunto appended.

I claim:

1. A gate comprising a platform, a swinging gate mounted upon the platform and including a shaft having one end disposed at right angles and extending below the platform, a weight carried by the extended end of the shaft, a lever pivotally mounted and 15 having one end curved to form a depression for the reception of the said weight, the opposite end of the lever being weighted.

2. A gate comprising a platform, a swinging gate mounted upon the platform and including a shaft having one end disposed at right angles and extending below the platform, a weight carried by the extended end of the shaft, a lever pivotally mounted and 20 having one end curved to form a depression for the reception of the said weight, the opposite end of the lever being weighted, connecting bars projecting toward the ends of the platform and connected to the gate at opposite edges thereof, and weighted links 25 pivotally connected to the connecting bars and the said platform.

3. A gate comprising a platform, a swinging gate mounted upon the platform and including a plurality of pickets, a shaft, a 30 plurality of yokes embracing the shaft and connected to the platform, a clamp member including plates embracing the pickets at the other lower ends and connected to the said shaft, connecting bars having their inner 35 ends connected to opposite edges of the gate, the outer ends of the connecting bars carry-

ing loops, and weighted means pivotally mounted and connected to the loop on the outer ends of the bars to normally maintain the pickets in upright position.

4. A gate comprising a platform, a swinging gate mounted upon the platform and including a plurality of pickets, a shaft, a plurality of yokes embracing the shaft, a clamp member including plates embracing the pickets at the other lower ends and connected to the said shaft, connecting bars having their inner ends connected to opposite edges of the gate, the outer ends of the connecting bars carrying loops, a weighted means mounted at each end of the platform including a pivoted link joined to the loop on the adjacent connecting bar, a weight joined to the said shaft and suspended therefrom, and means engageable with the said last mentioned weight for preventing swaying of the same when the gate is in upright position.

5. A gate comprising a platform, a swinging gate mounted upon the platform and including a plurality of pickets, a shaft, a plurality of yokes embracing the shaft, a clamp member including plates embracing the pickets at their lower ends and connected to the said shaft, connecting bars having 75 their inner ends connected to the opposite edges of the gate, the outer ends of the connecting bars carrying loops, weighted means mounted at each end of the platform including a pivoted link joined to the loop on 80 adjacent connecting bar and a weight joined to the said shaft and suspended therefrom, and a lever pivotally mounted and including a depressed portion adapted to receive the weight from the said shaft.

In testimony whereof I affix my signature in presence of two witnesses.

HERBERT M. WETHERINGTON.
